(57) **CLAIM**

The ornamental design for an adjustable weight bench, as shown and described.

DESCRIPTION

1. Adjustable weight bench

1.1 : Perspective

1.2 : Perspective

1.3 : Front

1.4 : Back

1.5 : Left

1.6 : Right

1.7 : Top

1.8 : Bottom

1.9 : Enlarged

1.10 : Enlarged

1.11 : Right view in a completely unfolded position

The parts shown by means of broken lines in the reproductions are not part of the claimed design; Fig. 1.9 is an enlarged view of a portion labeled “9” in fig. 1.1; Fig. 1.10 is an enlarged view of a portion labeled “10” in fig. 1.6; The dash dot dash lines in fig. 1.1, 1.6, 1.9, 1.10 and the label “9”

(Continued)

in fig. 1.1, label “10” in fig. 1.6 are for the purpose of depicting the cut line of the enlarged view and form no part of the claim.

1 Claim, 11 Drawing Sheets
